ETHEL PARSONS, OF NEW YORK, N. Y., ASSIGNEE TO THE STEARNS & FOSTER COMPANY, OF LOCKLAND, OHIO, A CORPORATION OF OHIO

DESIGN FOR TEXTILE FABRIC

Application filed November 28, 1930. Serial No. 37,804. Term of patent 3½ years.

To all whom it may concern:

Be it known that I, ETHEL PARSONS, a citizen of the United States, residing at New York, in the county of New York and State of New York, have invented a new, original, and ornamental Design for Textile Fabric, of which the following is a specification, reference being had to the accompanying drawing, forming part thereof.

In the drawing:

The figure is a plan view of a piece of textile fabric showing my design, a repeat unit of which is contained within the area outlined by dot and dash lines terminating in arrow heads, such unit being repeated in the relation indicated by the extension of the design on each side of the dot and dash lines.

I claim:

The ornamental design for textile fabric substantially as shown and described.

ETHEL PARSONS.
